BEALL, OF WASHINGTON, DISTRICT OF COLUMBIA

OIL AND NATURAL GAS CONVERSION PROCESS

Application filed October 15, 1929. Serial No. 399,801.

My invention relates to a process for converting hydrocarbons, such as mineral oils or constituents thereof, and natural gas or constituents thereof, into new and useful 5 commercial products such as motor fuels.

While motor fuel is specifically mentioned as one of the products of conversion, I do not wish to limit myself to the production of any specific product, as one of the advantages 10 of my process is its extreme flexibility, and by variations in operating conditions, which will be apparent to one skilled in the art, lighter, heavier or intermediate products such as kerosene, fuel oil and lubricating oil 15 may be obtained.

Furthermore, while I preferably employ natural gas as one of the initial constituents undergoing treatment, other gaseous hydrocarbons are contemplated within the scope of 20 my invention. The invention further contemplates the production of partial oxidation products from natural gas or other normally gaseous hydrocarbons, or gases containing the same by reaction with air or an oxidizing 25 gas under controlled temperature and pressure conditions. This partial oxidation product may be used for the subsequent production of motor fuel, etc., by reaction with a non-oxidized hydrocarbon according to the 30 preferred embodiment of my invention, or may be employed directly for other industrial uses. The invention also contemplates the production of motor fuel or similar products by reacting an oxidized hydrocarbon 35 produced preferably by oxidizing natural gas, but which may be obtained from other sources, with an unoxidized hydrocarbon, preferably in the full vapor phase under pressure in the presence of an inert gas.

40 The primary object of the invention is to produce motor fuel or other valuable materials by utilizing residuum oil and dry natural gas. By dry natural gas is meant gas consisting principally of the chemical constituents methane, ethane, propane and isobutane in varying proportions.

45 In order to effect a chemical conversion or combination between natural gas and oil by this method, it is desirable first to prepare a 50 partial oxidation product from the natural

gas, this oxidized material consisting principally of a complex mixture of organic aldehydes, alcohol, acids and ketones, which material may be termed "hydrocarbon oxides", by which term I mean partially oxidized hydrocarbons which are normally liquid, as distinguished from complete gaseous oxidation products such as hydrogen, carbon monoxide and carbon dioxide. This oxidized material under certain conditions of 55 heat and pressure has a very profound effect upon an oil. In some ways its action is similar to the action of aluminum chloride, as far as its decomposing and synthesizing effect is concerned. The reaction between this oxidized material and oil takes place best in the full vapor phase and under pressure substantially above atmospheric. In order to produce full vapor phase, an inert gas such as 60 may be injected nitrogen preliminary to the final zone of heat. Previously vapor phase has only been operated at comparatively low pressures and at high temperatures.

65 Of the two systems of treating oil, as heretofore practiced, vapor phase and liquid phase, vapor phase operates at a high temperature and low pressure, but produces a motor fuel of better quality and anti-knock value. This is offset by low yield. On the other hand, the liquid phase high pressure 70 process produces a greater yield of gasoline of poorer quality and less anti-knock value. The oil gas conversion process of the present invention has the combined advantages of 75 both the liquid and vapor phase processes, inasmuch as the vapor phase is maintained 80 under high pressure.

85 An additional advantage is gained by the action of the oxidized hydrocarbon material prepared from the natural gas. The process is not one of hydrogenation comparable to the Bergius process, but is rather one of dehydrogenation, because the combined oxygen of the oxidized hydrocarbon removes hydrogen from an unoxidized hydrocarbon oil and 90 combines with what would otherwise be free carbon to form ring compounds, carbon dioxide and carbon monoxide, water and products of partial oxidation. The entire effect 95 is beneficial as far as the production and 100

quality of motor fuel is concerned, because practically all of the aromatic series fall within the range of motor fuel, and the aromatic members of the series are noted as anti-knock compounds.

The process may be characterized as a conversion process as distinguished from the ordinary cracking or distillation processes. It is distinguished from ordinary conversion processes by the fact that it involves a reaction between a non-oxidized hydrocarbon and an oxidized hydrocarbon while in full vapor phase and under elevated pressure and temperature conditions, preferably in the presence of an inert gas.

I wish to stress particularly the commercial solution of the problem of oxidizing saturated gaseous hydrocarbons by the use of air. Secondly, the specific action of a product of partial oxidation upon an oil while in the full vapor phase and under elevated conditions of temperature and pressure. Another advantage of the process is the fact that the exothermic heats of reaction reduce the amount of auxiliary heat that would be necessary otherwise.

The process involves several improved steps which combine to produce improved industrial results, and several of the steps of the process are themselves individually novel. Consequently, while I will describe an improved process as a whole in the manner in which I prefer to carry it out, it will be apparent that I do not intend to limit my invention to the specific details to be hereinafter enumerated.

In carrying out my improved process, a hydrocarbon material, such as, for example natural gas, is heated under pressure, and air, or an oxygen-carrying gas, is separately heated, likewise under pressure, and the two heated gases are then contacted within a reaction zone. In carrying out the reaction the hydrocarbon material and the oxygen-carrying gas are preferably heated in a continuous heater or heaters of tubular design. From the reaction zone the gases and vapors are passed immediately into a zone of constant temperature. From the constant temperature zone, the reaction materials pass through knock-out or separating apparatus for the separation of liquid material.

Following the removal of liquid in the separator the gases and vapors are preferably passed into an absorber, where they are contacted with oil which is supplied to the absorber under pressure. This absorber may be of any standard design capable of withstanding the necessary pressure. The gases and vapors are, by this absorption step, stripped of practically all their constituents, with the exception of inert gases, such as, for example, nitrogen.

The oil, together with the absorbed material from the absorber and all the oxidized

hydrocarbon liquids from the knock-out or separator, pass into a mixing chamber where there is added a stream of vapors diverted from the main absorption step. Preferably from this stage the admixed vapors and oil pass through a zone of gentle heating, where the entire mixture is converted into the vapor phase prior to entering the final stage of heating. In the final stage of heating the desired reaction temperature is obtained. The reaction materials then pass into an enlarged space or reaction chamber or zone where sufficient time is allowed for the completion of conversion initiated in the final stage of heating.

Having hereinbefore described in a general way some of the important features of this process, I will now describe one specific method by which a person or persons skilled in the art may obtain certain desired results. It must be understood that this description is by way of illustration and that this process is by no means limited to this specifically described procedure.

For raw materials I may use (1) natural gas stripped of hydrocarbons suitable for constituent of motor fuel, (2) air, and (3) gas oil of thirty-five degrees Baumé. The proportions used of each may be in the following ratio: forty cubic feet of gas, fifty cubic feet of air, and one gallon of gas oil.

The gas and air may be separately compressed in two stages of compression as indicated in Fig. 2 to above 250 lbs., and preferably about 300 lbs. per square inch, or the gas and air may be compressed at this time to the final stage of compression, around 1200 to 1250 lbs. per square inch. The gas and air under compression pass through separate heating coils where the temperature is raised to from 360 to 420 degrees Fahrenheit, and preferably about 400 degrees Fahrenheit. While at this temperature, the gas and air are contacted in a reaction chamber by jetting the air in counter current to the entering gas. This is done by manifolding both air and gas into tubes of small diameter and of less square area than the total square area of the pipes in which they were separately heated. The cubical contents of the reaction zone is designed to meet the requirements of the plant. It is so constructed as to give a definite time of reaction with due allowance for time of admixture and increase of temperature. This reaction time is in the order of one-tenth to one second of time. A catalyst such as nitrous oxide in the proportion of one to two per cent of the volume of hydrocarbon gas used is beneficial in promoting and completing the reactions. Sponge platinum also assists in the reactions.

The reaction involved is exothermic in nature, and therefore means have to be provided for conducting away the heat generated. This is done by passing the reaction

products through a zone of constant temperature. A great many tubes of small diameter surrounded by steam under pressure of 500 lbs. per square inch, through which the gas is passed, serve this purpose. These reaction products, (vapors and gases) pass through a knock-out where some liquid is separated. If desired, the heated products may be employed for preheating the incoming gases by the use of suitable heat exchange apparatus (not shown). The uncondensed material passes through a third stage of compression, where the pressure is raised preferably to around 1200 to 1250 lbs. per square inch. If desired, the pressure may be originally raised to around 1200 to 1250 lbs. per square inch prior to the admission of the gas and air to the reaction chamber. While under this compression, these products pass through an absorption step, preferably of the counter-current type, where the ascending gas meets the descending stream of oil. This strips the gas of all its low partial pressure material, and the vented gas consists mostly of nitrogen. As there is a great deal of free energy left in the nitrogen after this amount of compression, it can be made to perform work in the way of driving turbines, motors or pumps, or it may be used upon expansion for purposes of refrigeration and cooling. The oil, together with the absorbed material, passes through steps previously described. This includes passing through a heat exchanger, then through a steam-to-oil preheater, where the temperature is raised to 500 degrees Fahrenheit, and then passes through a final stage of heating, where the temperature is preferably raised to approximately 785 degrees Fahrenheit. Following this final stage of heating, the reacting mixture then passes into an insulated reaction chamber of such diameter and length that the time of passage is approximately fifteen minutes.

The temperature is then reduced by passing through heat exchange to approximately 600 degrees Fahrenheit. While at this temperature, the mixture passes into a vent tank where the pressure is reduced to about 800 lbs. per square inch, and part of the inert or fixed gas may be vented off through suitable absorption medium in a third absorber, such as unused oil stock. The unvented product at a temperature of approximately 550 degrees Fahrenheit passes into a flash tower, where the pressure is reduced to 30 lbs. per square inch. The vapors from the flash tower pass to the fractionating tower, where gasoline or motor fuel at proper end point is fractionated out. This gasoline or motor fuel is preferably treated in the vapor phase by fuller's earth. The Gray process of treating is suitable for treating this type of vapor phase product. The bottoms from the fractionating tower and from the flash tower

may be returned through suitable heat exchange as recycle stock.

The temperatures and pressures given in the specific example set forth have been found to give good results. When the pressures are varied, I have found that the temperatures will be correspondingly varied. In other words, where the lower pressures are employed, greater temperatures are necessary, and vice versa. In all cases, however, pressures and temperatures substantially above atmospheric are employed in carrying out the process.

By this process operated as hereinbefore described in this specific example given, where the desired product is motor fuel, recycling unconverted material, the hydrocarbons of the mineral oil, together with the hydrocarbons of the natural gas, are practically quantitatively converted into hydrocarbons of a motor fuel characteristic and volatility. There are no residual tars; the tubes remain uncarboned; and carbon troubles experienced in processes heretofore employed are entirely eliminated. The motor fuel produced is of the highest anti-knock quality, of low Baumé gravity and high volatility.

The invention will be more readily understood by reference to the accompanying drawings showing diagrammatically forms of apparatus which may be employed in carrying out my process.

In the drawings:

Fig. 1 is a diagrammatic view of a form of apparatus for carrying out the process in which the pressures of the reacting hydrocarbon and air are raised to the full pressure prior to the reaction between said gases, and

Fig. 2 is a similar view showing an apparatus differing from Fig. 1 in that the pressures of the reacting hydrocarbon gas and air are raised to a pressure of 250-300 lbs. per square inch prior to reaction between them, and the reaction product raised to a higher pressure prior to reaction of this product with the unoxidized hydrocarbon.

Referring to Fig. 1 of the drawings, the numeral 10 denotes an inlet pipe through which air or other oxidizing gas is admitted into the system through a suitable meter 11, and thence through pipe 11' successively through compressors 12, 13 and 14, whereby the pressure is raised preferably to about 1200 to 1250 lbs. per square inch, and thence to a coil 15 heated by a gas flame or other suitable means 16. Preferably steam is admitted to the coil 15 through pipe 17 controlled by valve 17'. After passing from the heating coil 15, the oxidizing gases under pressure are admitted to a reaction zone 18 through perforated pipes or nozzles 19, where they are brought into intimate contact with natural gas or other hydrocarbon admitted through similar perforated pipes 130

28. Preferably a platinum screen 28' is interposed between the two sets of perforated pipes 19 and 28 to serve as a catalyst for initiating the reaction between the hydrocarbon gas and the oxidizing gas. Preferably also a catalytic gas such as nitrous oxide is admitted to the reaction zone through pipe 19'.

It is desirable that the hydrocarbon gas be heated entirely independently of the oxidizing gas and that both be supplied to the reaction zone under pressure. As shown, the natural gas is admitted through pipe 20, passing through a suitable meter 21 and pipe 21', and successively through compressors 22, 23 and 24, where the pressure is raised preferably to around 1200 to 1250 lbs. per square inch, and thence by way of pipe 25 into a heating coil 26, heated by a burner 27, and thence into the reaction zone by way of the perforated pipes 28. The period of reaction is preferably a short one, varying from 1/100 of a second to one second, and after passing through this zone, the reaction products pass immediately into a constant temperature zone 29, wherein excess heat is removed by means of a heat interchange device including steam pipes 30. The purpose of this constant temperature zone is to prevent the reaction from proceeding too far, and by means of this control, the desired quality of product may be obtained. The oxidized products and inert gases pass from the constant temperature zone through pipe 31 controlled by valve 32 into a separator 34, which separator may be provided with a valved offtake 35, whereby some of the liquid from this separator may be removed and utilized if desired. The separator has also a vapor offtake pipe 36 leading from the upper portion thereof, and a liquid offtake pipe 37 controlled by valve 38 leading from the bottom of the separator. A portion of the vapors passing from the separator through pipe 36 are led past valves 39 and 40 into an absorber 41, which absorber is provided with a vapor offtake 43 controlled by valve 43', through which nitrogen and other unabsorbed gases may be withdrawn. From the bottom of the absorber a pipe 44 leads to a mixing chamber 56.

Oil under pressure may be supplied to the absorber from an oil storage tank 45, through pipe 45' to pump 46, thence through pipe 42 containing valves 50 and 49 to the top of the absorber. Another pipe 47 leads from the pump 46 to an auxiliary absorber 51. A valve 48 is placed in the pipe 47 to control the quantity of oil passing into the auxiliary absorber. A pipe 52 leads from the top of the absorber and is controlled by valve 53, the purpose of this being to permit nitrogen and other unabsorbed gases to pass from the auxiliary absorber. From the bottom of the absorber, oil passes through pipe

54 and pump 55 to the primary absorber 41 and then out through pipe 44. The auxiliary absorber does not function in the initial stage of operation, and its function will be described more fully hereinafter.

The pipe 44 leading from the bottom of the primary absorber conducts oil and oxidized hydrocarbons to a mixing chamber 56. Into this mixing chamber inert gases are injected through by-pass 57 and valve 58, these gases coming from the separator 34 without passing through the absorber. The purpose of adding these inert gases is to convert the mixture of oxidized hydrocarbon material and non-oxidized hydrocarbon material introduced through the pipe 44 into the full vapor phase. Preferably also, I admit into the mixing chamber 56 oxidized hydrocarbons withdrawn from the bottom of separator 34 through the pipe 37, the quantity of such material being regulated by the valve 38.

After a thorough admixture in the chamber 56, the products are passed through a heat exchanger 59, where the temperature is raised to a still higher degree.

After leaving the preheater 61, the products pass through a heating coil 62, preferably heated by a gas burner 63, and from the heater to a reaction chamber 64. From the chamber 64 a pipe 65 leads back to the heat exchanger 59, where the gaseous products are cooled, at the same time heating the products passing in the other direction through heat exchanger 59, as previously described. From the heat exchanger 59, the products are passed through pipe 66, vent tank (already described in connection with Fig. 2) and pressure reducing valve 67', into a flash tower 66', where the pressure is reduced sufficiently to effect a rough separation of all the liquid materials falling within the range of motor fuel. The flash tower 66' is preferably provided with a pipe 67 leading to a safety valve 68. The tower has also a pipe 74 leading from the upper portion thereof and a pipe 70 leading from the lower portion, for returning liquid by way of pump 71, pipes 72 and 73, to the mixing chamber 56. The vaporized materials pass off from the upper portion of the flash tower through reduced pressure valve 69 and pipe 74 to a fractionating tower 75. A liquid offtake 76 from the bottom of the fractionating tower leads through pump 77 and pipes 72 and 73 to the mixing chamber 56. From the upper portion of the fractionating tower a pipe 78 conducts vapors to a vapor phase treater 79 of any suitable character, preferably containing fuller's earth. A goose neck 80 connects the lower portion of the fractionating tower to the bottom of the vapor phase treater 79, and serves as a liquid seal, serving also to return the heavy liquid products to the system.

From this treating chamber 79 the vapors pass through a water cooled condenser 81 through pipe 82 to a suitable separating tank 83, where the pressure is reduced sufficiently 5 to vent off high partial pressure vapors, and also nitrogen and other fixed gases through a pipe 85, pressure regulator 86, and thence through pipe 87 to the auxiliary absorber 51 previously described. In this auxiliary absorber 10 the gases are stripped of normally liquid constituents by meeting a counter-current of oil introduced through the pipe 47. The oil from the absorber, together with the absorbed material, is picked up and 15 passed into the system by means of the pump 55 previously described. From the separator tank 83, motor fuel or other final product may be withdrawn through pipe 84 and passed to a place of storage or use. 20 While the operation of the device is apparent from the above description of the apparatus, the following detailed description may be of assistance in understanding the functions of the various contributing 25 elements of the system.

Air and gas are metered in a proportion of one part of gas by volume to two and one-half parts of air. The pressure is elevated by means of the compressors to from 30 250 to 1200 to 1250 lbs. The gas and air passing through separate heating steps while under this compression is raised to from 350 to 900 degrees Fahrenheit, but preferably about 400 degrees Fahrenheit, where 35 the pressure is approximately 1200 to 1250 lbs. Where lower pressures are used, the higher ranges of temperature should be employed.

A pressure of 1200 to 1250 lbs. per square 40 inch is the optimum pressure and is preferably attained prior to the reaction zone, or if a lower pressure is initially employed, the pressure may be subsequently raised to around 1200 to 1250 lbs. per square inch as 45 previously described.

The two gases are then contacted within the reaction zone 18, but previous to this contact a small amount of oxide of nitrogen and/or steam is added to the air to act as a 50 catalyst to initiate the reaction. The reaction takes place between the gases upon admixture, and this reaction may be further facilitated by the screen 28 containing sponge platinum inserted midway between 55 the air and gas inlets 19 and 28. A high temperature is produced within the reaction zone, which, if allowed to proceed without the dissipation of heat for more than one second, would result in the products going 60 to carbon dioxide, carbon monoxide and water. Means for dissipating this heat of reaction are provided for by passing the reacting materials through a great number of small tubes surrounded by a steam jacket in 65 the constant temperature zone 29 under a

pressure sufficient to maintain a temperature around 500 to 550 degrees Fahrenheit. From this constant temperature zone 29, gases, vapors and liquid products of reaction pass without reduction of pressure through the 70 knock-out or separator 34, where a liquid material containing oxidized products separates out. The unliquefied material containing nitrogen from the top of the separator passes through the pipe 36 and valve 39 75 under high pressure. Part of the fluid stream is diverted through valve 40 into the absorber 41, where it meets a stream of un-oxidized oil entering through pipe 42, while another portion of the stream passes directly 80 into the mixing chamber 56 through pipe 57 and valve 58 without passing through the absorber. The relative quantities and pressures of the fluids passing into the absorber and mixer respectively are obviously regulated by means of the valves 39, 40 and 58. The pressure within the mixing chamber and subsequent heating and reaction zones should preferably be maintained at not substantially less than 1200 lbs. per square inch. The oil 85 passing from the absorber through pipe 44 is admixed with the liquid product entering through pipe 37 from the knock-out or separator 34, and the stream of vapors and gases is diverted from pipe line 36 through valve 90 58 into the mixing chamber 56. Following this mixing chamber, the products pass through heat exchanger 59 and from thence they may be passed through steam preheater 100 61, in order to raise the temperature sufficiently to effect vaporization preliminary to entering the final stage of heating. This step may be dispensed with if the heat exchange is sufficient to effect this vaporization without it. The mixture passing through 105 the final stage of heating at 62 in the full vapor phase and still maintained under 1200 lbs. pressure, enters the unheated reaction chamber 64, where sufficient time (from 5 to 15 minutes) is allowed for the reaction products to reach an optimum equilibrium for 110 producing the maximum amount of motor fuel. From the reaction chamber 64, the products pass through the previously described heat exchanger 59, which is preliminary to the steam preheater, and pass from this heat exchanger into the flash tower 66, where the pressure is reduced sufficiently to effect a rough separation of all the liquid materials falling within the range of motor 115 fuel. This vaporized material then passes through the fractionating tower 75, where the gasoline is fractionated to the required end point. The liquid products from the bottom of the flash tower at 70 and from the bottom of the fractionating tower at 76 120 are pumped back to the mixing chamber 56. The untreated vapors from the fractionating tower 75 pass before condensation through 125 vapor phase treatment with fuller's earth, 130

at 79. The vapors from the fuller's earth treatment pass through water cooled condenser 81 into tank 83, where the pressure is reduced sufficiently to vent off high partial pressure vapors, nitrogen and other fixed gases to the auxiliary absorber 51, where they are stripped of normally liquid constituents by meeting a counter-current stream of oil. The oil from the absorber, together with the absorbed material, is picked up and passed back into the system by means of pump 55 and repeats the cycle.

In the apparatus shown in Fig. 2, the arrangement of elements is the same as in Fig. 1, except that the gas and air are compressed to about 250-300 lbs. per square inch prior to their admission into reaction zone 18, and the vapors passing off from the separator 34 through pipe 36 are compressed to around 1200-1250 lbs. pressure in a subsequent stage of compression, which pressure is substantially maintained within the system up to and including the chamber 64, in which the oxidized and non-oxidized hydrocarbons are reacted. As shown, A and B denote air compressors, and C and D the gas compressors, by means of which pressure may be raised to an initial stage of compression, while E represents a compressor located within pipe line 36 by means of which the pressure may be boosted to the final stage of compression, around 1200-1250 lbs. per square inch. Apart from the compressors A, B, C, D and E, the apparatus shown in Fig. 2 is the same as that in Fig. 1.

The character of the partially oxidized hydrocarbons within the chamber 34 is dependent on the pressure maintained within the reaction zone 18, which pressure may be varied considerably. The pressure maintained within those portions of the system in which reactions between the partially oxidized hydrocarbons and the non-oxidized hydrocarbons take place is, however, preferably not substantially less than 1200 lbs. per square inch, which pressure may either be attained in successive stages as illustrated in Fig. 2 or may be attained prior to the reaction zone 18 as described and illustrated in connection with Fig. 1.

It will be understood that the process has been described with specific reference to the production of motor fuel, as a desired end product. The process, however, is very flexible and by variations of operation which will be apparent to one skilled in the art, lighter, heavier or intermediate products, such as kerosene, fuel oil and lubricating oil may be obtained.

Furthermore, valuable industrial products are obtained within the separator 34, which consists of partial oxidation products including aldehydes, alcohols, acids, ketones and the like. These may be withdrawn through the offtake 35 directly from the separator,

and may be employed for various industrial uses. These mixed products are useful without further purification for desulphurization of natural oils and natural gas frequently met with in certain oil fields. These partial oxidation products may be termed for convenience "hydrocarbon oxides."

Pure oxidation products may be obtained by employing a special gas introduced at 20 instead of the mixture of gases contained in 75 ordinary natural gas. By properly controlling conditions of time, temperature and pressure, the character and quality of the oxidation products may be controlled.

Likewise, while I preferably employ natural gas as one of the initial products undergoing treatment, nevertheless artificial gas, particularly a gas high in illuminants may be employed in place of the natural gas with certain modifications in the details of the 85 process. Thus one of the important features of the invention is an improved oxidation process which is capable of complete control by reason of the fact that the temperatures and pressure of the hydrocarbon gas 90 and the oxidizing gas are separately and independently regulated.

Other modifications of the process within the scope of the invention will be apparent to those skilled in the art. 95

What I claim is:

1. In a process for producing motor fuel by combining an oxidized hydrocarbon and an unoxidized hydrocarbon by the aid of heat and pressure, the step which comprises preparing the oxidized hydrocarbon by compressing and subsequently heating a normally gaseous hydrocarbon and an oxygen-carrying gas separately and then contacting the two gases in a reaction chamber exterior to the zone of compression while under pressure substantially above atmospheric and without prior admixture of the gases. 100

2. In a process as herein described, the improvement in oxidizing natural gas, which comprises preheating the natural gas and an oxygenating gas separately and under pressure, then immediately contacting the two gases in a reaction chamber separate from the zone of compression without prior admixture of the gases for a period of from 1/100 of a second to one second, and removing excess heat from the mixture. 110

3. An improved synthetic and addition process of partially oxygenating a normally gaseous hydrocarbon, which comprises preheating the hydrocarbon gas and an oxidizing gas separately and subsequently reacting the two gases in a chamber separate from the heating zone to produce liquid partial oxidation products in a single step directly from the original constituents. 120

4. An improved synthetic and addition process of partially oxygenating a normally gaseous hydrocarbon which comprises pre- 130

heating the hydrocarbon gas and an oxidizing gas separately and subsequently reacting the two gases in a chamber separate from the heating zone, controlling the temperatures of the reacting gases to prevent overheating, and controlling the time of the reaction to produce liquid partial oxidation products in a single step directly from the original constituents.

10 5. A conversion process of the character described, which comprises mixing a normally liquid, partially oxidized hydrocarbon with a normally liquid, unoxidized hydrocarbon under heat and pressure, and adding to the mixture sufficient inert gas such as nitrogen, to produce the full vapor phase under approximately 1200 pounds pressure per square inch, preliminary to the final stage of heating under substantially the same pressure, 15 then heating the entire mixture fully in vapor phase to produce hydrocarbon compounds of a different nature than the original materials.

6. A process of producing motor fuel comprising separately compressing and then heating a hydrocarbon in the vapor phase and an oxygen-carrying gas, then reacting the gases in a zone separate from the heating zone without reduction of pressure, limiting 20 the reaction period to from 1/100 to one second of time, maintaining the temperature of the reaction substantially constant, and the pressure at substantially 1200 lbs., adding a non-oxidized hydrocarbon in separate absorbing and mixing steps, adding to the mixture sufficient inert gas under pressure of approximately 1200 pounds per square inch to produce the full vapor phase of all constituents preliminary to a final stage of heating, 25 heating the mixture under substantially the same pressure and after the final stage of heating, continuously passing the entire mixture into a reaction chamber, maintaining said mixture in the reaction zone in the vapor phase for a sufficient time to allow for complete conversion and equilibrium, cooling the reaction products, reducing the pressure following the cooling step, further reducing the pressure in a separate zone for the purpose 30 of separating the more volatile and less volatile products of reaction, and returning the less volatile products to the system as recycle stock.

7. A process of oxidizing natural gas which 35 comprises separately and independently heating and compressing the natural gas and an oxidizing gas, then combining the two gases in a closed chamber separate from and independent of the compression zone, regulating the temperature of the reaction, and then separating the liquid and vapor products of the reaction.

8. A process for producing motor fuel by combining a normally liquid, partially oxidized hydrocarbon and an unoxidized hydro-

carbon which comprises initially preparing the partially oxidized hydrocarbon by heating an uncracked gaseous hydrocarbon and an oxygen-carrying gas separately and contacting the two gases in a reaction chamber under pressure substantially above atmospheric and then combining the reaction product with the unoxidized hydrocarbon by the aid of heat and pressure.

9. A process for producing motor fuel by combining a normally liquid, partially oxidized hydrocarbon and an unoxidized hydrocarbon the step which comprises initially preparing the partially oxidized hydrocarbon by heating a chemically saturated gaseous hydrocarbon and an oxygen-carrying gas separately and contacting the two gases in a reaction chamber under pressure substantially above atmospheric and then combining the reaction product with the unoxidized hydrocarbon by the aid of heat and pressure.

10. A process for producing motor fuel by combining a normally liquid, partially oxidized hydrocarbon and an unoxidized hydrocarbon which comprises initially preparing the partially oxidized hydrocarbon by heating an uncracked gaseous hydrocarbon and an oxygen-carrying gas separately and contacting the two gases in a reaction chamber under pressure substantially above atmospheric and without prior admixture and then combining the reaction product with the unoxidized hydrocarbon by the aid of heat and pressure.

11. The conversion process for producing motor fuel comprising mixing a normally liquid, partially oxidized hydrocarbon and a non-oxidized hydrocarbon under pressure, adding an inert gas to the mixture while under pressure of approximately 1200 lbs. to produce a full vapor phase, and subjecting the entire mixture without reduction of pressure to a temperature of approximately 785° Fahrenheit while fully in vapor phase in order to produce conversion of the constituents used into low boiling hydrocarbons including a motor fuel fraction.

12. A process for producing normally liquid, partially oxidized hydrocarbons from normally gaseous hydrocarbons and an oxidizing gas in a single reaction step from the original constituents, which process comprises compressing and heating the gaseous hydrocarbon, and separately compressing and heating the oxidizing gas, then passing the two gases without prior admixture and without reduction of pressure directly into and continuously through a reaction zone separate from the zones of compression.

13. A process for producing normally liquid, partially oxidized hydrocarbons from normally gaseous hydrocarbons and an oxidizing gas in a single reaction step from the original constituents, which process comprises compressing and heating the gaseous

- hydrocarbon, and separately compressing and heating the oxidizing gas, then passing the two gases without prior admixture and without reduction of pressure directly into and continuously through a reaction zone 5 separate from the zones of compression, and controlling the temperature of the reaction.
14. A process for producing normally liquid, partially oxidized hydrocarbons from normally gaseous hydrocarbons and an oxidizing gas in a single reaction step from the original constituents, which process comprises compressing and heating the gaseous hydrocarbon, and separately compressing and heating the oxidizing gas, then passing 10 the two gases without prior admixture and without reduction of pressure directly into and continuously through a reaction zone 15 separate from the zones of compression, and limiting the period of the reaction to from 20 1/100 to 1 second.
15. A process for producing normally liquid, partially oxidized hydrocarbons from normally gaseous hydrocarbons and an oxidizing gas in a single reaction step from the original constituents, which process comprises compressing and heating the gaseous hydrocarbon, and separately compressing and heating the oxidizing gas, then passing 25 the two gases without prior admixture and without reduction of pressure directly into and continuously through a reaction zone 30 separate from the zones of compression, and maintaining a temperature of approximately 35 400° F. within the reaction zone.
16. A process for producing normally liquid, partially oxidized hydrocarbons from normally gaseous hydrocarbons and an oxidizing gas in a single reaction step from the original constituents, which process comprises compressing and heating the gaseous hydrocarbon, and separately compressing and heating the oxidizing gas, then passing 40 the two gases without prior admixture and without reduction of pressure directly into and continuously through a reaction zone 45 separate from the zones of compression, and admitting NO₂ to the reaction zone.
17. A process for producing normally liquid, partially oxidized hydrocarbons from normally gaseous hydrocarbons and an oxidizing gas in a single reaction step from the original constituents, which process comprises compressing and heating the gaseous hydrocarbon, and separately compressing and heating the oxidizing gas, then passing 50 the two gases without prior admixture and without reduction of pressure directly into and continuously through a reaction zone 55 separate from the zones of compression, the reaction being carried out in the presence of a platinum catalyst.
18. In a process for producing motor fuel by combining a partially oxidized hydrocarbon and an unoxidized hydrocarbon, the 60 step which comprises preparing the oxidized hydrocarbon by compressing and subsequently heating a normally gaseous hydrocarbon, and separately compressing and subsequently heating an oxygen-carrying gas, and then 65 contacting the two gases while still under pressure greater than atmospheric in a reaction zone separate from the zones of compression without prior admixture of the gases. 70
19. In a process as herein described, the improvement which comprises compressing and heating a normally gaseous hydrocarbon, and separately compressing and heating an oxygen-carrying gas, then passing the two 75 gases without reduction of pressure into and continuously through a reaction zone separate from the zones of compression without admixture of the gases prior to the reaction zone, and controlling the period and temperature of the reaction to produce a normally liquid, partially oxidized hydrocarbon mixture from the original constituents in a single step. 80
20. A process for producing motor fuel 85 by combining a partially oxidized, normally liquid hydrocarbon and an unoxidized liquid hydrocarbon, which comprises initially preparing the partially oxidized hydrocarbon by compressing and heating a normally gaseous hydrocarbon, and separately compressing and heating an oxygen-carrying gas, then contacting the two gases in a reaction zone separate from the zones of compression 90 while still under pressure without admixture of the gases prior to their entrance into the reaction zone, and then combining the partially oxidized hydrocarbon obtained by such reaction with the unoxidized liquid hydrocarbon with the aid of heat and pressure. 95
21. A process for producing motor fuel, which comprises adding normally liquid, partially oxidized hydrocarbons to unoxidized, normally liquid hydrocarbons, converting the entire mixture into the full vapor 100 phase under pressure substantially greater than atmospheric, and producing a reaction between the two constituents by the aid of heat and pressure while fully in the vapor phase. 105
22. A conversion process for producing motor fuel, which comprises adding normally liquid partially oxidized hydrocarbons to unoxidized, normally liquid hydrocarbons, adding an inert gas, converting the 110 entire mixture into full vapor phase under a pressure substantially greater than atmospheric, and producing a reaction between the two constituents by the aid of heat and high superatmospheric pressure 115 while fully in vapor phase. 120
23. A process for producing motor fuel by combining a normally gaseous hydrocarbon and a normally liquid hydrocarbon, which comprises producing a normally liquid, par- 125

- tially oxidized hydrocarbon by reacting the gaseous hydrocarbon with an oxidizing gas under controlled temperature and pressure conditions, then admixing the partially oxidized liquid hydrocarbon with the non-oxidized hydrocarbon, adding an inert gas and converting the entire mixture into the full vapor phase under pressure of approximately 1200 lbs. per square inch, then reacting the constituents while fully in vapor phase without reduction of pressure at a temperature of approximately 785° F. for a period sufficient to allow substantially complete conversion and equilibrium of the constituents. 5
24. A continuous process for producing motor fuel by reacting a normally liquid, partially oxidized hydrocarbon and an un-oxidized hydrocarbon, which comprises initially preparing the partially oxidized hydrocarbon by continuously reacting a normally gaseous hydrocarbon and an oxygen-carrying gas by the aid of heat and pressure, continuously separating the gaseous portions of the partial oxidation product from the liquid portions, continuously stripping the low pressure gases from the gaseous portion by contacting the gaseous portion with incoming non-oxidized liquid hydrocarbon, and then combining the non-oxidized and the partially 20 oxidized liquid hydrocarbons with the aid of heat and pressure while fully in vapor phase. 25
25. A process for producing normally liquid, partially oxidized hydrocarbons from normally gaseous hydrocarbons and an oxidizing gas in a single reaction step from the original constituents, which process comprises compressing and heating the gaseous hydrocarbon, and separately compressing and heating the oxidizing gas, then passing the two gases without prior admixture and without reduction of pressure directly into and continuously through a reaction zone separate from the zones of compression, and admitting an oxide of nitrogen to the reaction zone. 30
26. A process for producing normally liquid, partially oxidized hydrocarbons from normally gaseous hydrocarbons and an oxidizing gas in a single reaction step from the original constituents, which process comprises compressing and heating the gaseous hydrocarbon, and separately compressing and heating the oxidizing gas, then passing the two gases without prior admixture and without reduction of pressure directly into and continuously through a reaction zone separate from the zones of compression, the reaction being carried out in the presence of a catalyst. 50
27. The herein-described process which comprises mixing a normally liquid, partially oxidized hydrocarbon with an unoxidized liquid hydrocarbon, continuously passing the entire mixture while under elevated temperature and pressure of not less than approxi- 60
- mately 1200 lbs. per square inch through a heating and reaction zone, and producing a conversion of the entire mixture into low boiling hydrocarbons including the motor fuel fraction without removal of any portion prior to the completion of the conversion in the reaction zone. 70
28. A conversion process of the character described, comprising mixing a normally liquid, partially oxidized hydrocarbon and a non-oxidized hydrocarbon under superatmospheric pressure, transforming the entire mixture while under superatmospheric pressure into the full vapor phase, and subjecting the entire mixture under superatmospheric pressure while fully in vapor phase to an elevated temperature sufficient to produce substantially complete conversion of the constituents used into lower boiling point hydrocarbons including the motor fuel fraction. 75
29. A conversion process of the character described, comprising mixing a normally liquid, partially oxidized hydrocarbon and a non-oxidized hydrocarbon under superatmospheric pressure, transforming the entire mixture while under pressure into the full vapor phase by the addition of an inert gas with the aid of heat, and subjecting the entire mixture under superatmospheric pressure while fully in vapor phase to an elevated temperature sufficient to produce substantially complete conversion of the constituents used into lower boiling point hydrocarbons including the motor fuel fraction. 80
30. A continuous conversion process of the character described, comprising mixing a normally liquid, partially oxidized hydrocarbon and a non-oxidized hydrocarbon under superatmospheric pressure, transforming the entire mixture while under superatmospheric pressure into the full vapor phase by the addition of an inert gas with the aid of heat, continuously passing the entire mixture while in full vapor phase into a reaction zone, and subjecting the entire mixture under superatmospheric pressure to an elevated temperature sufficient to produce substantially complete conversion of the hydrocarbon constituents used into lower boiling point hydrocarbons including the motor fuel fraction. 85
31. A process as in claim 30 in which a pressure of approximately 1200 lbs. per square inch is maintained during the conversion reaction. 90
32. A process as in claim 30 in which the mixture while in vapor phase is heated to approximately 785° F. 95
- In testimony whereof I affix my signature.

DISCLAIMER

1,859,193.—*Isaac N. Beall*, Washington, D. C. OIL AND NATURAL GAS CONVERSION PROCESS. Patent dated May 17, 1932. Disclaimer filed October 22, 1934, by the assignee, *John C. W. Beall*, the patentee, Isaac N. Beall, concurring.

Hereby enters this disclaimer limiting said claims of said patent as follows, to-wit:

1. From the scope of claim 3 he disclaims any interpretation except that wherein the medium for heating the oxidizing gas is separate and apart from the medium for heating the hydrocarbon gas and wherein said gases are initially contacted or brought together in the reaction chamber without prior admixture of the original constituents.

2. From the scope of claims 4 and 7 he disclaims any interpretation of "separately and independently heating and compressing the natural gas and an oxidizing gas" except that wherein the medium of heat supply for the natural gas is separate and apart from the medium of heat supply for the oxidizing gas and wherein the heat instantly generated by the initial contacting of the unmixed gases in the reaction zone is then subjected to a regulation to instantly check or control the reaction time to prevent overheating.
